AERONAUTICAL PROPELLER SPINNER

Thomas E. Doherty, Glastonbury, and Robert B. Keller, Simsbury, Conn., assignors to United Aircraft Corporation, East Hartford, Conn., a corporation of Delaware

Application October 28, 1954, Serial No. 465,416

8 Claims. (Cl. 170—135.743)

This invention relates to an aeronautical propeller spinner and, more particularly, to a spinner which is adapted to provide air cooling for the propeller with which it is associated.

In some modern aeronautical propeller installations, there has been a noticeable tendency towards propeller heating and overheating. This tendency will, of course, vary with flight conditions and atmospheric temperature encountered in flight and the tendency towards overheating also varies with the type of engine and propeller installation. In an exemplary installation, the propeller pitch change mechanism may be called upon to operate almost continuously in order to maintain a substantially constant propeller speed in different flight attitudes and in different altitudes of flight. This will cause the pitch change mechanism to become heated and, assuming an hydraulically controlled propeller, the hydraulic fluid will also become heated. While in most installations the normal flow of air over and around the propeller hub assembly is sufficient for propeller cooling purposes, in the exemplary installation there may be insufficient air flow for cooling purposes. That is, the propeller may be mounted on a large radial engine and there is the possibility that by reason of the large radial dimensions of the engine, a region of elevated ambient air pressure may be created in flight forwardly of the radial engine and there will be insufficient air flow in the propeller hub region to properly cool the propeller.

It is the general object of the invention to provide an aeronautical propeller spinner which will induce air flow in intimate contact with that portion of the propeller assembly which may require cooling.

Other more specific objects as well as advantages of the invention will become apparent to those skilled in the art from the following description of the annexed drawings which, by way of example only, illustrate two specific embodiments of the invention and in which,

Fig. 1 is a vertical longitudinal cross-sectional view of a spinner constructed in accordance with the invention;

Fig. 2 is a view similar to Fig. 1 but showing an alternative in construction; and

Fig. 3 is a detail cross-sectional view taken as indicated by the line 3—3 of Fig. 2.

For convenience in describing a spinner 10 which is constructed in accordance with the present invention, the said spinner is shown as associated with a four-blade propeller assembly comprising a hub or barrel H providing the principal support for the propeller blades which may be secured thereto in the locations designated at B, B. The particular propeller assembly shown also includes a dome D projecting forwardly of the hub or barrel H and which contains at least part of the propeller pitch changing mechanism and the hydraulic fluid for actuating the same. Thus, in the exemplary installation, it is most desirable to provide cooling for the dome D so as to reduce the temperature of the propeller control fluid and the pitch changing mechanism.

2

The spinner 10 which is particularly adapted for cooling purposes comprises a generally frusto-conically shaped shell which is made up of two sections, a front or nose section 12 which surrounds the dome D and a rear section 14 which surrounds the propeller hub H. The said front and rear sections 12 and 14 are joined in end-to-end relationship on a connecting ring 16, being secured thereto as by rivets 18, 18 or the like. The connecting ring 16 is generally L-shaped in cross section, having a radially inwardly projecting annular wall 20. A support ring 22, also of generally L-shaped cross-sectional configuration, is secured as by rivets 24, 24 to the inwardly projecting wall 20 so that one wall 26 of the support ring 22 projects longitudinally rearwardly of the spinner shell. A half-round soft rubber or rubber-like sealing and support strip 28 is cemented or otherwise secured to the inner surface of the longitudinally rearwardly projecting ring wall 26. This sealing strip embraces a longitudinally forwardly projecting wall 30 of a third L-shaped ring 32 which is secured as by bolts 34, 34 on the front face of the propeller hub section H.

The rear section 14 of the spinner shell has a plurality of blade openings 36, 36 through which the propeller blades project and detachable panels 38, 38 are provided in the spinner section 14 so that the shell can be placed on the propeller assembly from the front thereof. That is, the panels 38, 38 are removed from the section 14 and then the shell is thrust rearwardly over the propeller hub H so that the propeller blades are received within the openings 36, 36. Then the panels 38, 38 are replaced in the section 14. It will be seen that in the aforescribed spinner shell, the inner ring 32 is not detachable with the shell. The said ring 32 is secured on the hub and the shell is placed therearound so that the sealing strip 28 embraces the forwardly projecting wall of said inner ring 32.

It will be readily understood that the shell can be provided in more or less than the two sections shown and can be arranged for mounting on the propeller assembly in various other ways. In most cases, it will be desirable to provide additional spinner support means secured to the propeller assembly preferably rearwardly of the propeller blades. However, since a variety of additional support arrangements can be made in accordance with conventional practice, no specific arrangement is shown.

It is important to observe that the three-ring support arrangement, comprising the rings 16, 22 and 32, provides an imperforate annular bulk-head within the spinner 10 forwardly of the propeller hub H. The said annular bulkhead prevents the flow of air rearwardly thereof.

It is also important to observe that the front of the nose section 12 of the spinner shell is provided with a large central opening 40 for the flow of ram air in accordance with the present invention. Air passing through the opening 40 will flow around the dome D, as shown generally by the arrows, toward the three-ring annular bulkhead. While the nose section 12 does not snugly embrace the dome D, it is spaced relatively close to the front end portion of the said dome so that the annular passage defined therearound will constrain the air flow and force it into intimate association with the dome D. A generally cylindrical baffle or shroud 52 is secured within the nose section 12 as by rivets 44, 44 on a support ring 46 to surround the intermediate and rearward portion of the dome D in spaced relationship. As will be noted from the drawings, the shroud 42 is located in that part of the nose section of the spinner where the air stream passing rearwardly through the nose opening 40 would be permitted to expand. While the shroud 42 at its forward end does permit some expansion of the

air, and thus a velocity head decrease and a static head increase, it is provided to constrain the air flow in intimate contact with the dome D for effective cooling thereof. If the shroud were not provided, turbulence might be induced in the expanding air around the dome and cause inefficient propeller dome cooling.

In order that flow will be accommodated through the spinner 10, the nose section 12 of the spinner is provided with a plurality of circumferentially spaced segmental openings 48, 48 which preferably equal in number the propeller blades of the installation and which are preferably located so that one such opening 48 will be disposed between adjacent propeller blades. Each of the segmental openings 48, 48 is partially closed by a segmental louver-like panel 50 which is secured, as by rivets 52, 52, externally of the shell adjacent the front edge of the opening. The louver-like panels 50, 50 are provided to prevent turbulence in the air stream discharged through the openings 48, 48 and to direct the air in a smooth stream rearwardly of the spinner shell.

It will be apparent to those skilled in the art that in flight, the air pressure on the outside surface of the spinner shell adjacent the louvered openings 48, 48 will be considerably reduced by the jet pump or "scupper" effect of the panels 50, 50 and will be less than the external surface pressure adjacent the nose opening 40. In order to have discharge flow through the openings 48, 48, the internal air pressure adjacent the said openings must be greater than the external pressure. It is a feature of a spinner constructed in accordance with this invention that ram air in passing from the nose opening 40 to the discharge openings 48, 48 is not permitted to suffer pressure losses within the spinner to the point where internal pressure is equal to or less than external pressure at the said discharge openings. That is, the cylindrical shroud 42 is constructed and arranged to permit sufficient expansion of the ram air to increase its static pressure as required for efficient discharge while at the same time the ram air is constrained to flow in intimate contact with the dome D for efficient cooling thereof.

Considering air flow and pressures in the spinner in greater detail, it will be observed that the air undergoes a pressure increase due to impact as it enters the spinner nose opening 40. Immediately upon entering the said opening the air is permitted to expand as it passes over the forward portion of the dome D, it being observed that the annular passageway through which the air passes adjacent said forward dome portion increases in volume rearwardly by virtue of a rapid increase in its mean diameter. During such expansion of the air, its velocity pressure or head decreases and its static pressure or head increases. The forward portion of the shroud 42 adjacent the rivets 44, 44 permits the expansion to continue, but the remaining portion thereof provides an annular air passageway of substantially constant mean diameter and substantially constant cross-sectional area. Thus, expansion of the air ceases when it passes adjacent said remaining shroud portion and the velocity and static pressures of the air remain substantially constant until it reaches the trailing edge of said shroud where, prior to discharge, it again expands with an accompanying velocity pressure decrease and static pressure increase. By so limiting or controlling expansion of the air, the shroud 42 minimizes turbulence around the dome and provides for a smooth air flow thereover whereby to provide for efficient cooling of the same. The shroud 42 is so constructed and arranged, however, that it does not unduly limit air expansion with the result that static pressure will be inadequate for efficient discharge at the openings 48, 48. Stated differently, the shroud 42 controls expansion of the air so as to provide for efficient cooling and at the same time provides for internal pressure greater than external pressure at the discharge openings.

The actual size or radial dimension of the shroud 42 in any specific installation depends upon and is directly

related to the size or dimension of the nose opening 40. More specifically, the shroud is provided in a predetermined size according to the size of the nose opening so as to control expansion of the ram air for efficient cooling and to provide for internal pressure greater than external pressure at the discharge openings. The size or area of the nose opening 40 and the total area of the discharge openings 48, 48 and the speed of the aircraft control the volume of ram air flow through the spinner per unit of time. Accordingly, if an aircraft is expected to spend most of its flight time at or near one speed, which may be the cruising speed, the nose and discharge openings are selected to accommodate ram air flow in sufficient volume to take care of the anticipated propeller cooling requirements at said one speed. It should be understood, however, that a relatively large range of selection is permitted.

It should also be understood that the fore and/or aft location of the discharge openings 48, 48 is not critical and depends only upon external pressure conditions. That is, the said openings may be located forwardly of the propeller hub as shown, in the propeller hub region, or rearwardly thereof. If located adjacent or rearwardly of the hub, the ram air stream may provide additional propeller cooling in passing over the hub. However, external pressure conditions may not permit locating the discharge openings rearwardly of the position shown. For example, a large radial engine may create a region of high ambient pressure forwardly of its face. Under such conditions it may be impossible to discharge the ram air through discharge openings located adjacent or rearwardly of the propeller hub. In any location of the discharge openings 48, 48, the air tight bulkhead, such as provided by the annular rings, should be located adjacent to and rearwardly of the said openings to further constrain and direct flow of the ram air and to prevent undesirable, pressure-reducing expansion thereof.

In Fig. 2 there is shown a spinner which is identical to the previously described spinner. The only modification of the previously described construction is provided by the addition of an annular heat exchanger indicated generally by the reference numeral 51. The heat exchanger 51 has a hub 53 which embraces the dome D and may be considered a part thereof. That is, the hub 53 has a plurality of spiral grooves 54, 54 on its inner surface which circulate the propeller fluid therein. Such circulation of the propeller fluid is provided only for the purpose of cooling. To further facilitate the cooling of the propeller fluid, the heat exchanger 51 has a plurality of radially outwardly projecting extended surfaces or fins 56, 56 which extend to the shroud 42. Thus, when the ram air passes through the annular opening defined between the shroud 42 and the dome D, it will pass along the cooling fins 56, 56 to more efficiently cool the propeller fluid contained within the grooves 54, 54. Accordingly, propeller cooling may be enhanced by incorporating the heat exchanger 51 in the construction.

While we have described the invention in connection with two specific forms, it should be understood that the invention is not to be limited to the described forms otherwise than indicated by the claims which follow.

We claim as our invention:

1. In a cooling spinner for an aeronautical propeller of the type having a hub and a plurality of radially projecting blades, the combination comprising a generally frusto-conically shaped shell surrounding the hub in spaced relationship with its smaller diameter end projecting forwardly therefrom to provide the spinner nose, said shell having a nose opening to receive ram air and also having at least one radial opening spaced rearwardly of the nose to discharge the ram air stream, a louver-like panel secured to the shell forwardly of the discharge opening to direct the discharged air stream rearwardly of the spinner, an imperforate annular bulkhead extending between the propeller hub and the shell rearwardly

of but adjacent to the discharge opening to block rearward flow of the air stream in the spinner shell and to direct the air stream into the discharge opening, and a cylindrical shroud secured internally of the shell and extending substantially longitudinally thereof between the nose and discharge openings to direct air flow toward the central portion of the hub and to control expansion of the air stream for efficient cooling of the hub and at the same time to provide for an internal pressure greater than external pressure at said discharge opening.

2. In a cooling spinner for an aeronautical propeller of the type having a hub and a plurality of radially projecting blades, the combination comprising a generally frusto-conically shaped shell surrounding the hub in spaced relationship with its smaller diameter end projecting forwardly therefrom to provide the spinner nose, said shell having a nose opening to receive ram air and also having a plurality of circumferentially spaced radial openings located rearwardly of the nose to discharge the ram air stream, a louver-like panel for each of said discharge openings secured to the shell forwardly of its respective opening to direct air discharged therethrough rearwardly of the spinner, an imperforate annular bulkhead extending between the spinner shell and the propeller hub rearwardly of but adjacent to the discharge openings to block rearward flow of the air stream in the spinner and to direct the air stream into the discharge openings, and a cylindrical shroud secured internally of the shell and extending substantially longitudinally thereof between the nose and discharge openings to direct the ram air stream toward the central portion of the hub and to control expansion of the air stream for efficient cooling of the hub and at the same time to provide for an internal pressure greater than the external pressure at said discharge openings.

3. In a cooling spinner for an aeronautical propeller of the type having a hub, a plurality of radially projecting blades and a dome projecting forwardly of the hub and containing propeller pitch changing mechanism and hydraulic fluid therefor, the combination comprising a generally frusto-conically shaped shell surrounding the hub in spaced relationship with its smaller diameter end projecting forwardly and surrounding the dome to provide the spinner nose, said shell having a nose opening to receive ram air and also having at least one radial opening spaced rearwardly from the nose to discharge the ram air stream, an imperforate annular bulkhead extending between the propeller hub and the shell rearwardly of but adjacent to the discharge opening, and a cylindrical shroud secured internally of the shell and surrounding the dome in spaced relationship and in communication with the said nose opening to direct the ram air stream over the dome and to control expansion of the air stream for efficient cooling of the dome and at the same time to provide for an internal pressure greater than external pressure at said discharge opening.

4. In a cooling spinner for an aeronautical propeller of the type having a hub, a plurality of radially projecting blades, and a dome projecting forwardly of the hub and containing propeller control fluid, the combination comprising a generally frusto-conically shaped shell surrounding the hub in spaced relationship with its smaller diameter end projecting forwardly and surrounding the dome to provide the spinner nose, said shell having a nose opening to receive ram air and also having a plurality of circumferentially spaced radial openings located rearwardly of the nose to discharge the ram air stream, an imperforate annular bulkhead extending between the spinner shell and the propeller hub rearwardly of but adjacent to the discharge openings to block rearward flow of the air stream in the spinner and to direct the air stream into the discharge openings, and a cylindrical shroud secured internally of the shell and surrounding the dome in spaced relationship and in communication with the nose opening to direct the ram air stream around the dome and to

control expansion of the air stream for efficient cooling of the dome and at the same time to provide for an internal air pressure greater than external pressure at said discharge openings.

5. In a cooling spinner for an aeronautical propeller of the type having a hub, a plurality of radially projecting blades, and a dome projecting forwardly of the hub and containing propeller control fluid, the combination comprising a generally frusto-conically shaped shell surrounding the hub in spaced relationship with its smaller diameter end projecting forwardly and surrounding the dome to provide the spinner nose, said shell having a nose opening to receive ram air and also having a plurality of circumferentially spaced radial openings located rearwardly of the nose and forwardly of the propeller hub to discharge the ram air stream, an imperforate annular bulkhead extending between the spinner shell and the forward end of the propeller hub to block rearward flow of the air stream in the spinner and to direct the air stream into the discharge openings, and a cylindrical shroud secured internally of the shell and surrounding the dome in spaced relationship and in communication with the nose opening to direct the ram air stream around the dome and to control expansion of the air stream for efficient cooling of the dome and at the same time to provide for an internal air pressure greater than external pressure at said discharge openings.

6. In a cooling spinner for an aeronautical propeller of the type having a hub, a plurality of radially projecting blades, and a dome projecting forwardly of the hub and containing propeller control fluid, the combination comprising a generally frusto-conically shaped shell surrounding the hub in spaced relationship with its smaller diameter end projecting forwardly and surrounding the dome to provide the spinner nose, said shell having a nose opening forwardly of the dome and also having a plurality of circumferentially spaced radial openings located adjacent the rear end of the dome and forwardly of the propeller hub to discharge the ram air stream, a louver-like panel for each of the said discharge openings secured to the shell forwardly of its respective opening to direct air discharged therethrough rearwardly of the spinner, an imperforate annular bulkhead extending from the front end of the propeller hub to the spinner shell to block rearward flow of the air stream and to direct the air stream into the discharge openings, and a cylindrical shroud secured internally of the shell and surrounding the dome in spaced relationship and in communication with the nose opening to direct the ram air stream over the dome and to control expansion of the air stream for efficient cooling of the dome and at the same time to provide for an internal pressure greater than external pressure at said discharge openings.

7. Means for cooling an aeronautical propeller of the type having a hub, a plurality of radially projecting blades, and a dome projecting forwardly of the hub and containing propeller control fluid, said means comprising in combination, a generally frusto-conically shaped spinner shell surrounding the hub in spaced relationship with its smaller diameter end projecting forwardly therefrom and surrounding the dome to provide the spinner nose, said shell having a nose opening forwardly of the dome and also having a plurality of circumferentially spaced radial openings spaced rearwardly of the nose to discharge the ram air stream, an annular bulkhead between the propeller hub and the shell rearwardly of but adjacent to the discharge openings to block rearward flow of the air stream and to direct the air stream into the discharge openings, a cylindrical shroud secured internally of the shell and surrounding the dome in spaced relationship and in communication with the said nose opening to direct the ram air stream around the dome and to control expansion of the said air stream, and an annular heat exchanger surrounding the said dome within said shell and

having at least one passage for the flow of the propeller control fluid into and out of the dome.

8. Means for cooling an aeronautical propeller of the type having a hub, a plurality of radially projecting blades and a forwardly projecting dome containing propeller control fluid, said means comprising in combination, a generally frusto-conically shaped spinner shell surrounding the hub in spaced relationship with its smaller diameter end surrounding the dome in spaced relationship to provide the spinner nose, said shell having a nose opening forwardly of the dome to receive ram air and also having a plurality of circumferentially spaced radial openings rearwardly of the nose to discharge the ram air stream, an annular bulkhead extending between the propeller hub and the shell rearwardly of but adjacent to the discharge openings to block rearward flow of the air stream in the spinner shell and to direct the air stream into the discharge openings, a cylindrical shroud secured internally of the shell and surrounding the dome in spaced relationship to the shell.

10

15

ship and in communication with the said nose opening to direct the ram air stream around the dome and to control expansion of the said air stream, and an annular heat exchanger including a hub embracing the dome within the said shroud and having a passage for the flow of the propeller control fluid to and from the dome, and said heat exchanger also including a plurality of radial fins extending toward said shroud with their ends closely adjacent thereto.
